[57] CLAIM

The ornamental design for bank-teller terminal, as shown and described.

DESCRIPTION

FIG. 1 is a front perspective view from above of a bank-teller terminal showing my new design; FIGS. 2 and 3 are, respectively, an end elevation and a rear perspective view from below of the embodiment shown in FIG. 1;

FIG. 4 is a front perspective view from above of a second embodiment of the said design; and

FIGS. 5 and 6, are, respectively, an end elevation, and a rear perspective view from below, of the said second embodiment.

*Fig.1.**Fig.4.**Fig. 2.**Fig. 3.**Fig.5.**Fig.6.*
